UNITED STATES PATENT OFFICE.

OLIVER SKILTON PATTON, OF PHILADELPHIA, PENNSYLVANIA, ASSIGNOR
TO THE HENSEL, COLLADAY COMPANY, OF PENNSYLVANIA.

DESIGN FOR A SKIRT-PROTECTOR.

SPECIFICATION forming part of Design No. 28,463, dated April 12, 1898.

Application filed March 19, 1898. Serial No. 674,532. Term of patent 14 years.

To all whom it may concern:

Be it known that I, OLIVER SKILTON PATTON, a citizen of the United States, residing in the city and county of Philadelphia, State of Pennsylvania, have invented and produced a new and original Design for a Skirt-Protector, of which the following is a specification, reference being had to the accompanying drawings, forming part thereof.

- 10 The leading feature of my design for a skirt-protector is a head consisting of bars formed of parallel strands and longitudinal stripes crossing said bars and formed of links joined one with the other, as chains.
- 15 Figure 1 represents a face view of a piece of skirt-protector embodying my design. Fig. 2 represents a section thereof on line xx , Fig. 1. Fig. 3 represents a face view of a piece embodying my design on an enlarged scale.

In the drawings, A represents a piece of 20 skirt-protector, the same being formed of the head B and brush C. The head consists of the parallel strands D, forming transverse bars, and longitudinally-extending stripes E, which cross said bars at a right angle thereto 25 and are of the form of V-shaped links, which join each other, as chains.

Having thus described my invention, what I claim as new, and desire to secure by Letters Patent, is—

30 The design for a skirt-protector substantially as shown and described.

OLIVER SKILTON PATTON.
